UNITED STATES PATENT OFFICE.

JAMES PULLAR, OF HARTFORD, CONNECTICUT, ASSIGNOR TO THE INTERNATIONAL HORSE SHOE CO., INC., OF HARTFORD, CONNECTICUT, A CORPORATION OF CONNECTICUT.

HORSESHOE.

1,164,865.

Specification of Letters Patent. Patented Dec. 21, 1915.

Application filed February 20, 1915. Serial No. 9,491.

To all whom it may concern:

Be it known that I, JAMES PULLAR, a citizen of the United States, and a resident of Hartford, in the county of Hartford and State of Connecticut, have invented an Improvement in Horseshoes, of which the following description, in connection with the accompanying drawings, is a specification, like characters on the drawings representing like parts.

This invention relates to horse shoes and particularly to horse shoes of cast malleable metal.

In order that the principle of the invention may be readily understood, I have disclosed a single embodiment thereof in the accompanying drawing, wherein—

Figure 1 is an underneath plan of a horse shoe embodying my invention; Fig. 2 is a side elevation thereof; and Fig. 3 is an end elevation thereof looking toward the toe of the shoe.

Horse shoes as commonly constructed at the present time are hand or dropped forged and are provided with toe calks separately constructed and welded on during the process of manufacture. This renders the shoe expensive to make and involves a number of manipulations. Preferably, but not necessarily the shoe to which my invention is applied, is formed at a single operation, the body including the toe and heel calks being integral and cast of malleable metal.

Referring more particularly to the drawing, I have therein represented the horse shoe having a toe portion 1, an inner side 2 and an outer side 3. The shoe is provided with a toe calk 4 and heel calks 5 and 6. In accordance with the preferred embodiment of my invention, the shoe including the body and the said toe and heel calks is cast of malleable metal, preferably semi-steel or other durable metal. By casting the shoe, no hand labor thereon is necessary, and the shoe is ready to be applied after the casting process.

The shoes are preferably made rights and lefts, the one here shown being a right. It is preferably provided with a toe clip 7 extending from its upper face and preferably cast integral with the body.

The horse shoe herein shown is peculiarly adapted for use in winter, but the use thereof is not so restricted.

At least at one side of the shoe I provide

a heel calk having a plurality of wearing portions at an angle to each other. I have herein represented the outer heel calk 6 as so constructed and have herein shown the opposite or inner heel calk 5 as of usual formation; that is, as having a flat, relatively broad, wearing face 7. Within the scope of my invention, however, both heel calks may be constructed substantially as the heel calk 6 is here represented and described.

The heel calk 6, being at the outer side of the shoe, has an elongated, thin, wearing edge 8 extending in the same general direction as the side 1 of the shoe and an inwardly extending, thin, wearing edge 9, here shown as extending from the edge 8 at right angles thereto. Each of the portions of the heel calk terminating in the edges 8, 9 is preferably triangular in cross section, thus tapering to the wearing edges 8, 9. The construction of the heel calk is such that inward slipping is prevented, and the thinness of the wearing edges 8, 9 coöperates to this end.

The toe calk 4 in its preferred embodiment is provided with a thin, elongated, wearing edge 10 extending transversely of the shoe, and a second, thin, wearing edge 11 extending from the wearing edge 10 between its ends and at an abrupt angle thereto, thus furnishing angles 12 and 13. The wearing portions 10, 11 terminating in relatively thin edges are triangular in cross section, thus tapering to said edges substantially as described with reference to the portions of the heel calk 6. The construction and arrangement of the wearing edges 10 and 11 of the toe calk are such as to prevent outward slipping and to a lesser extent the wearing edge 11 serves to prevent inward slipping. Thus, the toe calk 4 and the heel calk 6 coöperate with each other to prevent both inward and outward slipping. I have herein represented the toe calk as having the wearing edge 11 at the outer side of the shoe, but within the scope and purpose of the invention, it may be at the inner side thereof, and similar portions may be arranged at both the inner and the outer sides.

Similarly, the lateral extension 9 of the heel calk may extend outwardly from the longitudinal portion 8 instead of inwardly, but the construction shown is preferred.

The shoe may be provided with any suit-

able means to attach the same to the hoof of the horse.

A horse shoe constructed in accordance with my invention has been found in practice to support the horse without slipping in either direction. Moreover the construction of a toe cark with its extension 11 is such as to prevent the toe cark catching in a slot or narrow opening.

Having thus described one illustrative embodiment of my invention, I desire it to be understood that although specific terms are employed, they are used in a generic and descriptive sense and not for purposes of limitation, the scope of the invention being set forth in the following claims.

Claims:

1. In combination with a horse shoe, a toe cark having one wearing portion extending transversely of the shoe and another wear-

ing portion extending from said first portion between its ends and at an inclination thereto and positioned to form respectively oblique and obtuse angles at its opposite faces with said transversely extending wear- 25

portion. 2. In combination with a horse shoe, a toe cark having one wearing portion extending transversely of the shoe and another wearing portion extending from said first portion between its ends toward the heel end of the shoe, and at an inclination to said transversely extending wearing portion. 30

In testimony whereof, I have signed my name to this specification, in the presence of 35 two subscribing witnesses.

JAMES PULLAR.
